(57) **CLAIM**

(21) Appl. No.: **29/376,989**

The ornamental design for a charging connector for electric vehicle, as shown and described.

(22) Filed: **Oct. 15, 2010**

DESCRIPTION

(30) **Foreign Application Priority Data**

Apr. 16, 2010 (JP) 2010-009668

FIG. 1 is a front, top and right side perspective view of a charging connector for electric vehicle showing our new design;

(51) **LOC (9) Cl.** **13-03**

FIG. 2 is a front, top and left side perspective view thereof;

(52) **U.S. Cl.** **D13/133**

FIG. 3 is a front elevation view thereof.

(58) **Field of Classification Search** D13/107–109,
D13/118–119, 133, 146, 147, 154, 184, 199;
D23/226; 320/104, 107–115, FOR. 104,
320/FOR. 119, DIG. 35

FIG. 4 is a rear elevation view thereof.

See application file for complete search history.

FIG. 5 is a right side elevation view thereof.

(56) **References Cited**

FIG. 6 is a left side elevation view thereof.

FIG. 7 is a top plan view thereof.

FIG. 8 is a bottom plan view thereof; and,

FIG. 9 is a front elevation view, in an alternate position

thereof.

The portion of the article shown in broken lines is for the

purpose of showing environmental structure only and forms

no part of the claimed design.

no part of the claimed design.
